DENTIFRICE-CONTAINING DEVICE AND
DENTIFRICE APPLICATOR THEREFOR

James F. Waters, New York, N. Y.

Application January 10, 1948, Serial No. 1,654

5 Claims. (Cl. 132—84)

1

This invention relates to aids for dental hygiene and more particularly to dentifrice-containing devices and applicators of dentifrices.

Among the objects of the invention is to provide a container for carrying a tooth brush and a readily available dentifrice which may be taken from the container by the brush in such quantity as is desired for dental use.

Another object of the invention is to provide a dentifrice dispensing device suitable for carrying on the person and comprising a closed container for a tooth brush and dentifrice.

Another object of the invention is to provide a dentifrice-containing device capable of being replenished with dentifrice in the nature of refills or applicators, each of which constitutes a dentifrice in either paste, fluid or powder form spread over a sheet of flexible material or the interior surface of a sheath, or a cake of dentifrice so shaped as to be contained within the containing device.

Another object of the invention is to provide a package of dentifrice comprising a single unit, or a stack of several units, each unit containing a liquid or paste dentifrice so arranged as to be placeable in a containing device from whence the dentifrice may be removed in desired amounts until the contained dentifrice is consumed, whereupon the used package may be removed and replaced by a fresh package.

Other objects and uses of the invention will appear from a detailed description of the same, which consists in the features of construction and combinations of parts hereinafter described and claimed.

In the drawings,

Fig. 1 shows the interior of a dentifrice-containing device in a longitudinal section;

Fig. 2 is a cross-sectional view on line 2—2 of Fig. 1;

Fig. 3 is a view of the containing device of Fig. 1 and illustrating the manner of applying dentifrice to a brush;

Fig. 4 illustrates a package of dentifrice consisting of a single applicator unit;

Fig. 5 illustrates a package of dentifrice consisting of a number of applicator units;

Fig. 6 illustrates a package of dentifrice consisting of a sheath lined with dentifrice.

Fig. 7 illustrates a package of dentifrice consisting of a stack of individual applicators; and

Fig. 8 shows a longitudinal section of a dentifrice-containing device with a solid cake of dentifrice.

The present invention provides a container for enclosing a tooth brush and a personal supply of dentifrice. Dentifrice in such form as to satisfy the particular desire of a user is provided in package or other form for refilling the container when an original supply becomes depleted. The dentifrice may be any of the conventional

2

tooth pastes or liquid dentifrices, or a dry or wet layer prepared with moistened tooth powder, or loose powder, or a dry tubular cake of dental powder in molded form. While the container may assume a variety of shapes, I have shown in the drawings a container consisting of a cylindrical casing 10 having an opening 11 at one end which is closeable with a removable cap 12 that snugly engages a collar 13 at the open end of the casing. The casing and cap may be made of metal or of other suitable material and so constructed as to be air-tight.

The upper portion and interior of the collar 13 provide a bearing surface for a ring 14 which can be removed from the casing when it is desired to replenish the dentifrice in the casing. A knurled rim 15 on the ring 14 extends beyond the collar 13 for facilitating gripping the ring for disengaging it from the casing.

20 The ring 14 has fastened to it a perforated sleeve 16 which normally extends inwardly of the casing. The perforated sleeve is preferably made in such a manner as to permit flexing of the sleeve when pressure is applied laterally thereto. The sleeve may be an open-woven wire gauze, or a screen mesh of neutral materials such as synthetic organic plastics or glass fibers, or a perforated sheet of synthetic organic plastics, rubber or metal. The dentifrice is located between the perforated sleeve 16 and the wall of the casing 10.

25 The meshes or openings in the sleeve should be of such size and in such number as to permit the passage therethrough of the particular dentifrice employed, or to provide for the passage therethrough of the ends of the bristles of a brush. Wire mesh screens ranging in gauge from 22 to 50 are satisfactory for the various forms of dentifrice described herein.

30 In Figs. 1, 2 and 3 there is illustrated a dentifrice applicator intermediate the wall of the casing 10 and the screen 16. An applicator is a device by which dentifrice in any form may be presented to and made accessible to the exterior of the perforated screen. It may consist of a flexible carrier or pad 17 of absorbent material, with or without a backing, such as a sized cotton gauze 18, and either a paste or a liquid dentifrice 19 applied to the face of the pad, Fig. 4. 35 The pad may be made of any textile or other suitable materials and the backing may be dispensed with when the carrier 17 has such properties as to serve the function of the backing. For inserting an applicator into the casing 10 the ring 14 and perforated screen 16 are withdrawn from the casing and the applicator is wrapped or applied about the screen with the dentifrice in contact with the screen. As thus assembled, the screen and the applicator are inserted within the casing. The space between the screen and the

wall of the casing is sufficient to accommodate a fresh applicator.

A supply of fresh applicators can be provided in the form of a roll, Fig. 5, which consists of backing material 20, a carrier or pad 21, dentifrice 22 in paste or fluid form, and a sheet of glassine or condenser paper 23 for separating the dentifrice from the reverse surface of the backing material. These various layers of materials are in such width as to cover the screen of a particular dispensing device and of such length as to provide a plurality of applicators for individual use, say to provide for six or a dozen individual applicator units. Scored lines or markings 24 are provided for determining the circumferential measurement required for each applicator to envelop a perforated sleeve. An applicator is detached from the roll as needed. The intervening sheet of paper 23 is removed and cast aside before an applicator is applied to the screen.

In Fig. 6, there is illustrated a sheath or stocking 25 of knitted or woven textile material lined with dentifrice 25' and of such size as to fit over the tubular screen 16 with the dentifrice between the sheath and the screen. The screen 25 is introduced into the sheath and then the assembled sheath and screen is inserted into the casing of the containing device.

Another manner for providing individual applicators is illustrated in Fig. 7 in which a plurality of individual applicators are stacked, each applicator consisting of a backing 26, a pad 27, and dentifrice 28, and each applicator being separated by a sheet of non-porous paper 29. The stack of applicators or individual applicators in any of a variety of forms may be packaged in an hermetically sealed container for insuring continued freshness of the dentifrice.

The interior of the perforated sleeve or screen 16 provides a receptacle for a tooth brush 30 and the receptacle is sealed by a stopper 31 affixed to the handle of the brush. The stopper 31 firmly engages the opening in ring 14, and together with the ring, closes off the opening at the end of the casing 10. The brush and the dentifrice are thereby contained in a sealed enclosure when they are not being used.

The manner of collecting dentifrice on the brush is illustrated in Fig. 3. When a paste or other flowable dentifrice is employed some of the dentifrice will come through the perforations in the sleeve 16 when the flexible applicator is wrapped about the sleeve. As the dentifrice is consumed in use, more dentifrice can be collected on a brush upon flexing the sleeve by the brush as shown in Fig. 3. The lateral pressure provided between the wall of the casing 10 and the brush 30 directs and diffuses the dentifrice 32 through the perforations in the sleeve so that the dentifrice can be collected on the bristles of the brush in the quantity desired.

In Fig. 8 there is shown a dispensing device 33 in which the dentifrice 34 consists of a tubular cake of relatively dry dentifrice comprising dental powder in molded form. The cake is slipped over the perforated sleeve 35. When this type of dentifrice is used the screen may be quite coarse so as to permit access to the cake by the brush bristles, or if desired, the perforated sleeve may be omitted entirely. If desired, the space 70 between the perforated sleeve or screen 35 and the wall of the casing 36 may be filled with loose powder (not shown). In such event the screen should be of sufficiently fine mesh to serve as a waffled support for the powder while at the same

time permit the powder to pass through the meshes when disturbed by the bristles of a brush.

The dispensing device of the present invention may be made in a variety of sizes for home use and for travelling with applicators available in the respective sizes required.

What is claimed is:

1. In a device for dispensing dentifrice wherein an elongated casing having an open end contains a perforated sleeve which forms a central chamber within itself and an annular chamber between the perforated sleeve and the casing, said sleeve being removably supported in said casing by a ring carried by said sleeve and engaging the casing adjacent its open end, the combination with said perforated sleeve of a carrier for dentifrice wrapped around the sleeve with the dentifrice carried thereby lying in contacting relationship with the exterior of the sleeve.

2. The device set forth in claim 1 in which the perforated sleeve is flexible and capable of flexing under pressure exerted thereagainst from within its central chamber to cause the dentifrice carried thereby to diffuse inwardly through the perforations in the screen.

3. The device set forth in claim 1 in which a closure is provided for said central chamber, said closure being formed to engage with said ring and be supported thereby.

4. A tubular device for supporting a dentifrice preparation, comprising a sleeve formed by a relatively thin wall for supporting a layer of dentifrice preparation on the exterior surface of the sleeve, said sleeve having a plurality of openings through its wall which are distributed over substantially the full area of the wall, and a dentifrice preparation forming a layer overlying the exterior surface of said wall and from which the preparation is supplied to said openings for making the same available from within said sleeve, said sleeve being open at one end and having an open bore with a cross-sectional area sufficiently large to enable manipulation of a tooth brush against the interior surface of said sleeve to gather from said openings a supply of the dental preparation.

5. The article defined in claim 4 in which the sleeve is a flexible gauze-like material adapted to permit the passage of the dentifrice preparation therethrough.

JAMES F. WATERS.
